(74) Attorney, Agent, or Firm — Michael Best & Friedrich LLP

(57) **CLAIM**

I claim the ornamental design for a laminating cartridge refill, as shown and described.

DESCRIPTION

FIG. 1 is a first perspective view of a laminating cartridge refill embodying the present invention;

FIG. 2 is a second perspective view thereof;

FIG. 3 is a top view thereof;

FIG. 4 is a front view thereof;

FIG. 5 is bottom view thereof;

FIG. 6 is a left side view thereof;

FIG. 7 is a right side view thereof; and,

FIG. 8 is a rear view thereof.

The broken lines represent portions of the laminating cartridge refill that form no part of the claimed design.
